DESIGN FOR A COMBINATION LATCH AND LOCK

Berthold R. Thiele, Milwaukee, Wis., assignor to
E. R. Wagner Manufacturing Company, Mil-
waukee, Wis., a corporation of Wisconsin

Application February 21, 1944, Serial No. 112,662

Term of patent 14 years

(Cl. D50—5)

To all whom it may concern:

Be it known that I, Berthold R. Thiele, a national of Germany, residing at Milwaukee, in the county of Milwaukee and State of Wisconsin, have invented a new, original, and ornamental Design for a Combination Latch and Lock, of which the following is a specification, reference being had to the accompanying drawing, forming a part thereof, and in which:

Figure 1 is a front elevation of a combination latch and lock showing my new design; and
Figure 2 is a side elevation thereof.

I claim:

The ornamental design for a combination latch and lock, as shown.

BERTHOLD R. THIELE.
